DESIGN FOR A BOX BLANK OR SIMILAR ARTICLE

Frank McIntosh, New York, N. Y., assignor to Lenthalic, Incorporated, New York, N. Y., a corporation of New York

Application September 30, 1941, Serial No. 103,568

Term of patent 7 years

To all whom it may concern:

Be it known that I, Frank McIntosh, a citizen of the United States, residing at New York city, in the county of New York and State of New York, have invented a new, original, and ornamental Design for a Box Blank or Similar Article, of which the following is a specification, reference being had to the accompanying drawing, forming part thereof.

In the drawing the figure is a plan view of a box blank or similar article embodying my new design.

The characterizing feature of my design for the box blank shown resides in the specific surface ornamentation thereon as illustrated in the drawing figure.

I claim:

The ornamental design for a box blank or similar article, substantially as shown and described.

FRANK McINTOSH.
